UNITED STATES PATENT OFFICE.

WILLIAM C. H. WEFEL, OF DENVER, COLORADO.

ELECTRIC-LIGHTING SYSTEM.

Application filed March 19, 1923. Serial No. 626,076.

To all whom it may concern:

Be it known that I, WILLIAM C. H. WEFEL, a citizen of the United States, residing at Denver, in the county of Denver and State 5 of Colorado, have invented certain new and useful Improvements in Electric-Lighting Systems, of which the following is a specification.

My invention relates to a system for automatically regulating the current flow in electric lighting circuits and its primary object is to provide in a circuit of this character an electric magnetic appliance which by the temporary inclusion of a supplemental coil in the course of current flow, 15 renders said flow equable from the moment the circuit is completed.

My invention is particularly adapted for use in a series electric lighting circuit in 20 which in the event of an interruption in the current flow in any lamp unit by breakage of the lamp filament or other similar cause, a resistance substantially equivalent to that produced in the lamp, is automatically connected in the circuit.

The resistance circuit is closed by the switch when the electromagnet is in its normal inactive condition and is opened only when, after the circuit has been closed in the 30 line, the lines of magnetic force produced in the magnet are sufficient to open the switch and it will be apparent that before the resistance circuit is thus opened, the current in a lamp unit the filament of which is intact, will be split with substantially equal portions going through the lamp and the resistance as long as the lines of magnetic force are insufficient to open the switch and that the consequently decreased resistance 35 in said unit will cause the lamps of other units in the series to receive an overload of current, while the lamp in the unit in which the current has been split will incandesce dimly until the resistance in every lamp 40 unit of the series has been opened.

My invention as outlined hereinbefore corrects this fault by the temporary inclusion of an auxiliary coil in the path of the current through the magnet of each lamp 45 unit, which causes the magnet to immediately open the shunt in which the resistance is included the moment the current flow commences and thereby compels the entire current to pass through the filament of the lamp.

My invention is also of value in lighting

systems in which a shunting appliance of the above described character is not provided since by the automatic inclusion of the auxiliary coil in the circuit during the initial 60 supply of current, the current flow is retarded and thereby prevented from rushing to the lamps in the series at more than its normal voltage, which ordinarily causes a temporary flaring of the light produced in 65 the lamps and is injurious to the filaments of the same.

In the accompanying drawings, I have shown my invention in operative relation to an incandescent lamp fixture equipped with 70 a resistance and an electromagnet for connecting it in the circuit by incapacitation of the lamp as hereinbefore explained, and since the operation of the invention in connection with fixtures without this resistance is substantially the same, I did not believe it 75 necessary to exemplify the same by further illustration.

In the construction and arrangement of 80 elements shown in the drawings and herein-after to be explained, my invention has been embodied in practical and simple form but I desire it understood that variations in the arrangement and electrical connections of said elements may be availed of without departing from the spirit of the invention 85 as defined in the hereunto appended claims.

In the drawings in the two views of which corresponding parts have been similarly designated by numerical characters of reference.

Figure 1 represents a partially diagrammatic view of the co-operating elements of the fixture and their electrical connections as assembled upon the lower surface of a 95 non-conductive base, the electric switch forming part of the system having been shown in side elevation and the lamp-socket having been shown in superposed relation to the base, with the object of clearly delineating the courses of the current flow between the different elements, and

Figure 2, a sectional elevation of the fixture in a plane indicated by the line 2-2, 100 Figure 1.

Referring to the drawings, the reference numeral 2 designates a circular base-plate of non-conductive material upon the under-surface of which the co-operating elements of the fixture and their electrical connections are assembled in compact arrangement.

The base is in practice, fastened against

a car ceiling or other suitable support by means of screws or bolts and it carries an escutcheon 3 which covers the operating elements mounted upon its lower surface and which at the same time gives a finished and artistic appearance to the fixture as an entirety.

A lamp-socket 4 of conventional construction is mounted centrally of the escutcheon 10 to place an incandescent bulb 5 in the circuit, and a shade 6 is suspended from the escutcheon around the socket to deflect the light of the lamp.

Two resistance coils 7 fastened upon the 15 base are connected in series by a wire 8 and the electromagnetic switch which controls the connection of the resistance in the circuit and which in its entirety is designated by the numeral 9, is likewise fastened to the 20 base in convenient adjacency to the socket and the coils.

The switch comprises a conductive spool 10 mounted between and in electric connection with two hangers 12 which are suspended from the base by screws 13. The core and inner surfaces of the spool are covered with layers of insulating material for the support of the windings of the electromagnet.

30 The armature 14 of the magnet is pivotally mounted as at 15 in a bearing at the lower end of one of the hangers 12 and it has at its free end a contact blade 16 which controls the current flow by engagement 35 with one or the other of two contacts 17 and 18 at the lower ends of posts 19 and 20 which are fastened to the base in insulated relation to each other. A coiled spring 21 attached at its ends to an extension of the 40 armature and the upper end of the hanger on which the armature is supported, serves to hold the armature normally in engagement with the contact 17.

45 The spool of the electromagnet supports in addition to the ordinary coil, a second coil of lesser current-carrying capacity and correspondingly greater resistance which for convenience is wound upon the other.

50 The first mentioned coil which will hereinafter be referred to as the main coil or windings, is designated in Figure 1 of the drawings by the reference numeral 22, while the additional coil of relatively greater resistance, hereinafter to be referred to as the auxiliary coil or windings, has been shown 55 at 23.

60 The fixture is connected at opposite sides of a break in one of the line wires 24 and 25 of the electric circuit through the medium of binding posts 26 and 27 on the base.

65 The two windings 22 and 23 have a common connection 28 with the contact 18 on the post 20 and the opposite end of the main coil 22 is connected to the binding post 26 of the line wire 24 by means of a conductor

29 in which the lamp-socket is included through the medium of its terminals 30 which in practice are connected by the filament of the lamp.

The opposite end of the auxiliary windings 23 is connected to the binding post 27 of the line wire 24 through the medium of a conductor 31, the connection between the windings and said conductor being made through the intermediary of one of the 75 hangers 12 of the conductive magnet spool 10.

The two resistance coils 7 the combined ohmic resistance of which slightly exceeds that of the lamp filament, are connected in series in a shunt 32 of the conductor 29 80 which connects the main windings of the electromagnetic switch with the line wire 24, and included in this shunt are the spool 10 of the magnet and the armature 14 of the same when it engages with the contact 17.

The shunt is formed by connecting an end of one of the connected resistance coils in the line through the medium of the binding post 26 and connecting the opposite end 90 of the other coil with the contact 17.

When the circuit in which the fixture is included is open, the armature of the electromagnetic switch is held in a position of rest 95 upon the contact 17 by the coiled spring 21 and if subsequently, the circuit is closed in the line, the current passes initially through both windings of the electromagnet and owing to the greater number of the auxiliary windings immediately produces 100 sufficient lines of magnetic force to attract the armature.

The course of current in this initial flow is beginning at the source of electricity 33, the line wire 24, the conductor 29 including 105 the lamp filament, the main coil 22 of the electromagnetic switch, the auxiliary coil 23 and the line wire 24 at the opposite side of the break.

The lines of magnetic force produced in 110 the magnet by the current flow through both its coils, cause the armature to move immediately into engagement with the contact 18 and by its disengagement from the contact 17 breaks the shunt in which the resistance coils are connected and thereby excludes 115 said coils from the path of the current.

With the armature in this position the current flow is as follows:

Beginning at the source of electricity 33, 120 the line wire 24, the conductor 29 including the lamp filament, the main coil 22 of the electromagnetic switch, the connection 28, the armature and the conductive spool of the magnet, the conductor 31 and the line wire 24 at 125 the opposite side of the break.

It will be understood from the above description that owing to the flow of current through an auxiliary magnet coil of greater 130 resistance supplemental to that through the

main coil, the resistance 7 is instantly excluded from the path of the current as soon as the lamp circuit is closed; and that in consequence the lamp will immediately incandesce to its full capacity without the period of dimness ordinarily experienced in the operation of lamp fixtures of the type shown and described, it being apparent that without the aid of a coil of greater resistance, the main coil of the magnet could not produce sufficient lines of magnetic force to attract the armature until after the current has attained its full voltage.

When the lamp is in its normal operative condition as hereinabove explained, the current flow is mainly through the main winding of the magnet, it being obvious that by reason of its greater resistance but little current will pass through the lighter windings.

With a normal voltage, sufficient lines of magnetic force are produced in the main windings to maintain the armature in engagement with the contact, so that the auxiliary windings function only at the beginning of the operation and are practically inactive under normal operating conditions.

In case the filament of the lamp is broken or the lamp is otherwise incapacitated, the magnet is de-energized and the current is shunted through the resistance coils along the following course:

Beginning at the source, the line wire 24, the shunt 32 including the resistance coils 7, the contact 17, the armature which after deenergization of the magnet was moved to its original position by the spring 21, the conductive spool of the magnet, the conductor 31 and the line wire 24 at the opposite side of its break. By including the resistance in the circuit immediately upon breakage of the lamp filament, through the automatic action of the electromagnet switch, the current flow through the other lamps of the series is continued and each lamp of the series will remain in operation as long as the circuit is closed, irrespective of the condition of the other lamps.

When the invention is employed in a circuit not provided with resistance shunts, the initial flow of current when the circuit is first closed will be retarded by the inclusion of the coil of greater resistance until the armature is withdrawn from the contact 17 as before, and an excess of current to the lamp filament is thereby prevented.

Having thus described my invention, what I claim and desire to secure by Letters Patent is:

1. In a system of regulating the current flow in an electric lighting circuit, a circuit, a lamp therein, an electromagnet including a main coil and an auxiliary coil connected in the circuit in series with each other and the lamp, and a switch closed by

the magnet and connected in the circuit to provide a by-path around the auxiliary coil, the combined resistances of the two coils being high enough to restrict the initial flow of current to the lamp and the two coils being relatively arranged for conjoint magnetic action to operate the switch.

2. In a system of regulating the current flow in an electric lighting circuit, a circuit, a lamp therein, an electromagnet including a main coil and an auxiliary coil connected in the circuit in series with each other and the lamp, and a switch actuated by the magnet and connected in the circuit to provide a by-path around the auxiliary coil after the magnet has been energized, the combined resistances of the two coils being high enough to restrict the initial flow of current to the lamp and the two coils being relatively arranged for conjoint magnetic action to operate the switch.

3. In a system of regulating the current flow in an electric lighting circuit, a circuit, a lamp therein, an electromagnet including a main coil and an auxiliary coil connected in the circuit in series with each other and the lamp, a shunt in the circuit around the auxiliary coil, and an armature-switch connected in the shunt to close the same by energization of the magnet, the combined resistances of the two coils being high enough to restrict the initial flow of current to the lamp and the two coils being relatively arranged for conjoint magnetic action to operate the switch.

4. In a system of regulating the current flow in an electric lighting circuit, a circuit, a lamp therein, an electromagnet including a conductive spool, and a main coil and an auxiliary coil connected in the circuit in series with each other and the lamp, a shunt in the circuit around the auxiliary coil providing a path for current through the main coil including the conductive spool, and an armature-switch connected in the shunt to close the same on energization of the magnet, the combined resistances of the two coils being high enough to restrict the initial flow of current to the lamp and the two coils being relatively arranged for conjoint magnetic action to operate the switch.

5. In a system of regulating the current flow in an electric lighting circuit, a circuit, a lamp therein, an electromagnet including a main coil and an auxiliary coil connected in the circuit in series with each other and the lamp, a normally closed shunt in the circuit around the lamp, a resistance in said shunt, a shunt in the circuit around the auxiliary coil, and an armature-switch connected in the shunts to open the first mentioned shunt and close the other shunt on energization of the magnet, the combined resistances of the two coils being high enough to restrict the initial flow of current to the lamp.

and the two coils being relatively arranged for conjoint magnetic action to operate the switch.

6. In a system of regulating the current flow in an electric lighting circuit, a circuit, a lamp therein, an electromagnet including a conductive spool, a main coil and an auxiliary coil connected in the circuit in series with each other and the lamp, a normally closed shunt in the circuit around the lamp, a resistance in said shunt, a shunt in the circuit around the auxiliary coil, providing a path for current through the main coil

including the conductive spool, and an armature-switch connected in the shunts to open the first mentioned shunt and close the other shunt on energization of the magnet, the combined resistances of the two coils being high enough to restrict the initial flow of current to the lamp and the two coils being relatively arranged for conjoint magnetic action to operate the switch. 15 20

In testimony whereof I have affixed my signature.

WILLIAM C. H. WEFEL.
